(57) **CLAIM**

I claim the ornamental design for the shoe insert, as shown and described.

DESCRIPTION

FIG. 1 shows a top, front, right perspective view of a shoe insert in accordance with the present invention;

FIG. 2 is a front elevational view of the shoe insert of FIG. 1;

FIG. 3 is a rear elevational view of the shoe insert of FIG. 1;

FIG. 4 is a left side elevational view of the shoe insert of FIG. 1;

FIG. 5 is a right side elevational view of the shoe insert of FIG. 1;

FIG. 6 is a top plan view of the shoe insert of FIG. 1;

FIG. 7 is a bottom plan view of the shoe insert of FIG. 1;

FIG. 8 is a left side elevational view of the shoe insert of FIG. 1 showing an area of enlargement;

FIG. 9 is a right side elevational view of the shoe insert of FIG. 1 showing another area of enlargement;

FIG. 10 is a view of the area of enlargement of the left side elevational view of FIG. 8; and,

FIG. 11 is a view of the area of enlargement of the right side elevational view of FIG. 9.

1 Claim, 10 Drawing Sheets
